UNITED STATES PATENT OFFICE.

MORRIS KOPPELMAN, OF BROOKLYN, NEW YORK, AND WINFIELD H. MAPES, OF GLEN RIDGE, NEW JERSEY, ASSIGNEES TO HOLED-TITE PACKING, INC., OF WILMINGTON, DELAWARE, A CORPORATION OF DELAWARE, AND MAPES CONSOLIDATED MANUFACTURING COMPANY, OF WILMINGTON, DELAWARE, A CORPORATION OF DELAWARE.

EGG CARRIER.

Application filed May 11, 1927. Serial No. 190,408.

The improvements relate to devices for packing, carrying or otherwise transporting and holding eggs and other fragile articles. Devices of this character are commonly called carriers, and usually consist of a box or carton in which the fragile articles are held and enclosed, and by which they are protected against breaking. The present improvements provide a carrier of this character which will effectively hold and protect the articles and may be used not only for the delivery and carrying of eggs in small quantities, but may be employed for the packing of them in crates of standard size, containing thirty dozen eggs, and may also be used, without a crate for shipping or mailing eggs in limited quantity.

Among the objects and advantages of the present improvements—which will be described as applied to egg carriers—are the following: The construction of the carrier in such a manner that it may be shipped, packed and stored when empty as a flat sheet, with the holders nested, so that the carriers will occupy a minimum of space and will protect one another against any shock or strain tending to crush or deform them; to adapt the said carrier to use in crates or boxes for the purpose of packing, positioning and protecting them therein, after the manner of the "flats" shown and described in Letters Patent of the United States No. 1,429,207 of September 12, 1922; to provide sufficient ventilation for the eggs when packed or stored; to enable the vendor or user in quantity to remove the eggs from the crate in dozen or other lots, without handling them individually, examine them or exhibit them without removing them from the carrier, and enable the purchaser in small quantities to safely carry them and keep them on hand for consumption in the original packing; and to provide firm yet yielding individual egg holders in combination with a stiff and strong wrapper or container for a number of them.

The improvements are illustrated in the accompanying drawings, in which—

Fig. 1 is a front view in perspective of an egg carrier in open position embodying the

improvements, and with the honeycomb fillers at one end broken away; and

Fig. 2 is a similar view of a carrier in closed position showing a modification or variation in the application of the improvements.

The outer folding box or carton comprises the bottom 1, front 2, with slot 2', back 3, top 4 and closing flap 5 with tongue 5' adapted to be passed through the slot 2' to hold the carton in closed position. Secured to the inside of the bottom 1, by means of light wire staples 7, or other suitable fastening means, is a sheet of material 6, preferably made of relatively soft felted wood fibres or other fibres having thereon, and preferably formed integral therewith, upwardly extending ring-like protuberances 8 surrounding the concave central portions 9. These members are of substantially the same form as the "flats" described and shown in the patent above referred to, and may be formed in the manner described, in that patent, so as to be relatively rigid yet yielding, but constantly tending to return to normal position, and thereby affording a firm somewhat yielding and gripping "cushion" support for the eggs. The wrapper or carton, on the other hand, should be made of stiff strong material, such as paper board which has been pressed or ironed in its making, so that it will form a protecting receptacle that will not yield to ordinary shocks and strains and will form an outer box or carton of sufficient strength to prevent ordinary pressures or impacts from compressing or deforming it. It will be seen that the entire unitary structure is such that the sheets may be placed flat upon one another with the protuberances in nested relation. If desired, this outer carton may be provided with flaps or other means for closing its ends, but this is not a part of the present improvements, and is not essential to their embodiment. The "flats" 6 and their cup-like holders may also be made integral with the outer box or carton, if desired, but if this is done some means should be employed to render the sheets 6 carrying the holders stiff and strong, like the other sides of the carton. This may be done by pressing or ironing the

sheets between the holders, or by making them—and the holders also, if desired—of sufficient weight and thickness to give the requisite strength and rigidity, as the form and arrangement of the holders is such that they tend to increase the strength of the bottom sheet and reinforce it.

In the modified form illustrated in Fig. 2, the top, 4', is provided with a series of round holes 4" corresponding in size and shape to the rings 8, which form a part of a sheet similar to 6, and having substantially the same diameter as the outer diameter of said rings, so that the bases of the rings rest on the inside 15 of the cover around the openings, are supported by and support it, while the dome-like central portions 9 surrounded by the rings are supported only by the said rings at their perimeters. These dome-like central portions 20 do not extend to the plane of the base, and may therefore be depressed to some extent and yield to receive and protect the eggs held therein without permitting those held by one ring to come in contact with those above or below it. This is also important because eggs 25 vary to some extent in length, and because provision is thus made for the accommodation of extra long eggs. The bottom of the wrapper or carton is provided with holes similar to 30 the holes 4" in the top, and the arrangement of the holes with respect thereto is the same. It is within the purview of the present improvements to have either the top or the bottom of the carton provided with the openings 35 or to have both so provided, and to have top or bottom or both provided with the holders. The preferred embodiment is illustrated in the drawings, and in this form the flat 6 is secured to the bottom of the carton, so that it 40 is reinforced and stiffened thereby, thus providing a strong bottom and at the same time a relatively yielding set of holders. It will be understood that where only one side (i. e. the top 4 or bottom 1) is provided with holes similar to 4", the nesting relation of the unfolded carton is accomplished by stacking them 45 with the perforated sides alternately on the right and the left respectively, whereby the protuberances of the flats of the imperforated sides nest in the holes of the perforate sides.

In the use of the present improvements honeycomb fillers 10 consisting of the usual intersecting vertically arranged strips of sheet material are employed, the lower edges 55 of the filler being positioned and held against lateral movement between the holders, and the filler having its opposite and side edges in contact, or in close proximity to, the other walls of the carton, so that the carton is filled and 60 braced thereby, and so that each egg, 11, will be held in position and isolated from the others. It will be seen that the cartons herein described and shown may be filled with eggs and placed in crates of standard size, in closed position, and that when the form of Fig. 1 is em-

ployed they may be so packed in open position, with the side 3, cover 4 and flap 5 extending vertically, one carton being superposed upon another, and the sides comprising the parts just named overlapping. When the eggs are 70 removed from the crate or box the cartons may be taken out with the eggs in them, and the eggs examined, exhibited to and delivered to purchasers therein, and the eggs carried away by the purchaser and kept in the carton until 75 actually used. The carton itself may be made of any desired material, and when used for mailing or shipping without a crate, may be made of sheet metal or other very strong and rigid material, so as to securely protect its 80 contents.

We claim:

1. In a device of the character described, a sheet of material adapted to be folded and to form a receptacle for fragile articles having a plurality of sides on opposite sides of the said articles, holders for said articles on one side of the sheet consisting of relatively yielding material having inwardly extending unbroken protuberances of the same material, said foldable sheet of material being relatively stiff and strong as compared with the material of the holders, said holders and foldable sheet being composed of separate pieces of material secured together. 95

2. A carton for fragile articles comprising a foldable sheet of stiff material adapted to form opposite sides of an enclosing container, a sheet of softer material on a portion thereof of which forms one of said sides, said latter sheet having inwardly extending substantially unbroken protuberances adapted to engage the articles, the construction and arrangement being such that all of the said parts form a unitary structure having a stiff resistant outer shell and a yielding inner holding cushioning portion. 100

3. A carton for fragile articles comprising a foldable sheet of stiff material adapted to form opposite sides of an enclosing container, inwardly extending substantially unbroken protuberances adapted to engage the articles on a portion of said sheet which forms one of said sides, said protuberances being formed of material less rigid in character than the material of the sheet, the construction and arrangement being such that all of the said parts form a unitary structure having a stiff resistant outer shell and a yielding inner holding cushioning portion. 115

4. In a device of the character described, a sheet of material adapted to be folded and to form a receptacle for fragile articles having a plurality of sides on opposite sides of the said articles, holders for said articles on sides of said sheet which are opposite when folded consisting of relatively yielding material having inwardly extending protuberances of the same material, said sheet having openings opposite the protuberances of one of said hold- 125 130

ers, all of said parts being connected and constituting a unitary structure and said holders being hollow and adapted to be nested with other similar holders on other similar sheets 5 above and below them.

5. In a device of the character described, a sheet of material adapted to be folded and to form a receptacle for fragile articles having a plurality of sides on opposite sides of the 10 said articles, holders for said articles on one side of the sheet consisting of relatively yielding material having inwardly extending pro-

tuberances of the same material, said foldable sheet of material being relatively stiff and strong as compared with the materials of the 15 holders, said foldable sheet being provided with openings opposite the said holders, said foldable sheet and holders being integral.

Witness our hands this 3rd day of May, 1927, at the city, county and State of New 20 York.

MORRIS KOPPELMAN.
WINFIELD H. MAPES.
